Specification for Design.

Patented July 26, 1921.

Application filed June 24, 1920. Serial No. 391,546. Term of patent 14 years.

To all whom it may concern:

Be it known that I, CHARLIE GASTON, a citizen of the United States, and resident of Chicago, in the county of Cook and State of Illinois, have invented a new, original, and ornamental Design for a Pressure-Indicating Gage, of which the following is a specification, reference being had to the accompanying drawing, forming part thereof.

The figure is an elevation of a pressure indicating gage showing my new design.

What I claim is:

The ornamental design for a pressure indicating gage, as shown.

CHARLIE GASTON.
